FIBER CONTAINER

Frank J. O'Brien, Pelham, N. Y., assignor to Continental Can Company, Inc., New York, N. Y., a corporation of New York

Application June 10, 1943, Serial No. 490,325

2 Claims. (Cl. 229—5.5)

The invention relates to new and useful improvements in containers made from paper, cardboard, and other fibrous materials.

An object of the invention is to provide a fiber container wherein the body portion is tightly sealed and closed after the product is placed therein by non-metallic closure members without the use of adhesives.

A further object of the invention is to provide a container of the above type wherein the body portion is closed by a sealing disk of relatively thin material which is pressed into tight sealing engagement with the inner wall of the body portion by a heavy fiber retainer disk.

Another object of the invention is to provide a container in which the body wall includes an outer cylindrical member and an inner liner member contacting therewith, and wherein said container after it is filled, is closed by a sealing disk extending all the way across the open end of the container and folded down onto the outer wall thereof, said sealing disk having a depression therein after it is applied to the container, which depression is surrounded by a cylindrical wall contacting with the inner wall of the liner, and wherein heavy fiber retainer disks are disposed in said depression and dimensioned so as to force the cylindrical wall into tight sealing contact with the liner.

A further object of the invention is to provide a container of the above type with a reclosure cover which is secured to the body portion by a sealing tape.

In the drawing—

Figure 1 is a sectional view through a container embodying the improvements.

Figure 2 is an enlarged section of a portion of the container at the closure end thereof.

Figure 3 is a view similar to Figure 2, but showing a slightly modified form of the wall structure of the container.

The improved container includes a body 1 which is preferably cylindrical. This body portion is made of paper or other fibrous material. The body wall may be made from a web which is convolutely wound or from a web which is spirally wound. Disposed within the container is a liner 2, which is preferably formed of fibrous material treated so as to be moisture-proof and/or oil-proof, depending upon the purpose for which the container is to be used. This liner 2 terminates at the bottom end at 3, which is spaced away from the lower end of the body portion 1. Placed in the lower end of the body and 55

against the end of the liner wall is an end liner 4, of similar material to the liner 2.

Inserted in the body against the outer face of the end liner 4 is an end member 5 which is provided with a flange 6 projecting outwardly from the end member 5. This flange which terminates short of the lower end of the body wall 1 is initially formed, and then the body wall is rolled or curled around the flange and against the inner face thereof and also against the under face of the end member 5. This forms a very strong, durable seam for joining the bottom end member to the body of the container.

At the upper end as shown in Figure 2, the liner terminates at 7, which is a short distance below the end 8 of the body wall 1. This completes the body of the container, and after it is filled with the chosen product, then the body is closed and sealed by a sealing disk 9. This sealing disk 9 is laid across the open end of the body and a retainer disk 10 dimensioned so as to fit fairly tight within the liner is placed against the sealing disk 9 and the disk is forced down into the liner. This forms a depression in the sealing disk which is surrounded by a cylindrical wall 11, and this cylindrical wall is clamped tightly against the liner 2 by this retainer disk 10. This forms a seal which prevents the contents from passing around the end of the liner. As shown 30 in Figure 2, a second retainer disk 12 is placed against the sealing disk 9. This retainer disk 12 is dimensioned so as to make a substantially tight fit within the inner wall of the body 1. The result is that a second depression or step is formed 35 in the sealing disk 9 which is surrounded by a cylindrical wall 13, and this cylindrical wall 13 is clamped against the inner wall of the body 1 so as to provide a tight seal therewith. This sealing disk 9 extends beyond the limits of the body wall 1 and is bent downwardly at 14 against the outer wall of the container body. When the retainer disks are forced to their seats in the container body, the sealing disk is so firmly pressed into tight sealing contact with the liner and body that no adhesive is necessary to complete the seal. The packer merely places the sealing disk across the open end of the container and forces the retainer disks against the sealing member and into the body and these retainer disks become a physical closure means for completing the closing of the container body.

No other closure means is necessary for the sealing of the container, but it is preferred to provide a slip cover for the container which may be used for reclosure purposes when the con-

tainer is opened and which may also be used to provide a second or auxiliary seal for the complete package.

This reclosure member as shown in Figure 2 includes a disk 15 which is provided with an outwardly extending flange 16 arranged substantially at right angles thereto. A collar 17 is provided and the disk 15 is inserted therein leaving a portion of the upper part of the collar which is rolled or curled inwardly as at 18 against the inner face of the flange and the outer face of the member 15. These parts are preferably secured together by any suitable adhesive. The collar 17 is dimensioned so that it makes substantially tight frictional fit with the outer wall of the container body 1. The sealing disk 9 is folded downwardly as indicated at 14 and the collar at 17 contacts therewith and holds it in its folded position and pressed against the outer wall of the container so as to further insure a seal between the body wall and the sealing disk 9. Furthermore, a sealing tape 19 is applied so as to lap partway onto the collar 17 or skirt of the reclosure member and partway onto the body wall. This makes a final seal for the container and it also holds the reclosure cover in assembled position on the closed container.

When it is desired to open the container the tape is cut along the lower edge of the collar and then the reclosure cover is removed. This exposes the outer retainer disk 12 which may be pried out and then the closure disk 10 can be pried out and the sealing disks ruptured so as to provide an opening through which the contents may be removed. This sealing disk 9 is preferably made of Cellophane or glassine or some other suitable lining material which is impervious to moisture. This sealing disk may also be treated or made of a material which is oil-proof. After the container is opened so as to give access to the contents, the reclosure cover may be applied at any time for temporarily closing the container.

In the form shown in Figure 3 the liner 2 is extended as indicated at 7a so that it projects beyond the end 8a of the body wall 1. In this form of construction a retaining disk 10a and a retaining disk 12a, both of the same diameter, are placed against the sealing disk 9 so that it is forced down into a liner, providing a cylindrical portion 11a which is tightly pressed by the retainer disks into sealing engagement with the inner surface of the liner 2. This sealing disk extends over the edge of the liner and downward, as indicated at 14a, where it contacts with the outer wall of the liner. The reclosure member is formed with a collar 17a which is so dimensioned that it makes a frictional contact with the depending portion 14a of the sealing disk and holds it in tight engagement with the outer wall of the liner. The closure tape 19 overlaps the lower end of the collar and the

adjacent upper end of the body wall and forms a final seal. Instead of providing two disks 10a and 12a, a single disk may be used in lieu thereof.

While the sealing disk is described above as held in tight sealing contact by the inserted oversize retainer disk, it may be desirable in some instances to use an adhesive for securing the sealing disk to the body of the container. Any form of sealing material may be used, but preferably a thermoplastic sealing material which is applied to the peripheral portion of the sealing disk before it is attached to the container. If this thermoplastic sealing material is applied to the underface of the sealing disk in the region where it will make contact with the inner side and end of the body wall, then heat may be applied to the disk when it is attached to the end and will be caused to firmly adhere thereto.

It is obvious that many changes in the selection of the materials and the details of construction may be made without departing from the spirit of the invention as set forth in the appended claims.

I claim:

- 25 1. A fiber container comprising a cylindrical body portion, a liner therefor, a sealing disk extending across the open end of said body portion for closing the same, said sealing disk having a central depression surrounded by a cylindrical wall dimensioned so as to contact with the inner wall of the liner and a relatively flat retainer disk located wholly in said depression and filling the same, said retainer disk being dimensioned so that the peripheral edge thereof will engage 30 the cylindrical wall of the sealing disk and force the same into tight sealing engagement with the inner wall of the liner, said sealing disk being extended over the end of the liner and folded downward onto the outer wall of the container.
- 35 2. A fiber container comprising a cylindrical body portion, a liner therefor, a sealing disk extending across the open end of said body portion for closing the same, said sealing disk having a central depression surrounded by a cylindrical wall dimensioned so as to contact with the inner wall of the liner and a relatively flat retainer disk located wholly in said depression and filling the same, said retainer disk being dimensioned so that the peripheral edge thereof will engage 40 the cylindrical wall of the sealing disk and force the same into tight sealing engagement with the inner wall of the liner, said sealing disk being extended over the end of the liner and folded downward onto the outer wall of the container.
- 45 3. A fiber container comprising a cylindrical body portion, a liner therefor, a sealing disk extending across the open end of said body portion for closing the same, said sealing disk having a central depression surrounded by a cylindrical wall dimensioned so as to contact with the inner wall of the liner and a relatively flat retainer disk located wholly in said depression and filling the same, said retainer disk being dimensioned so that the peripheral edge thereof will engage 50 the cylindrical wall of the sealing disk and force the same into tight sealing engagement with the inner wall of the liner, said sealing disk being extended over the end of the liner and folded downward onto the outer wall of the container, 55 and a removable slip cover of fiber material adapted to close said container, said cover having a depending collar which contacts with the folded down portion of the sealing disk and clamps the same against the outer wall of the container.
